DRY MAT SCORCHER

Frank Milne, Calgary, Alberta, Canada

Application May 7, 1931. Serial No. 535,794

4 Claims. (Cl. 34—16)

This invention relates to an improved dry mat scorching of the type used in drying matrices, the object being to form an improved construction where the matrix may be dried quickly without warping, unequal shrinkage, wrinkling or buckling.

Another object of the invention is to provide a mat scorching formed to provide a pressure on the mat during the drying operation.

10 A further object, more specifically, is to provide a mat scorching having a mat receiving heating structure and means coacting therewith when closing the heating structure and pressing a mat against the structure during the drying operation.

In the accompanying drawings—

Figure 1 is a side view of a mat scorching disclosing an embodiment of the invention.

20 Figure 2 is a perspective view of a pair of frames used to form part of the structure shown in Figure 1.

Figure 3 is an end view of the structure shown in Figure 1.

25 Figure 4 is a horizontal sectional view through Figure 1 on line 4—4.

Referring to the accompanying drawings by numerals, 1 indicates legs associated with suitable braces 2 forming a stand. Preferably there are four legs 1 each formed with an angle iron 30 and braced by suitable braces 2. On top of these legs is placed a cast iron base 3 which is bolted or otherwise secured rigidly to these legs. Suitable end plates 4 extend upwardly from the base plate 3 which with the steel covering plate 5 35 form a chamber. This chamber is divided by an arc-shaped casting 6 whereby the space 7 may be termed a heating chamber by reason of the electric heating coils 8 carried by the casting 6. These heating coils are connected to a suitable 40 source of current (not shown). A switch 9 is interposed in the circuit of the various heating coils 8, said switch being what is known as a three-heat switch which will provide current so as to heat the coils to three different temperatures. A desirable structure has been found to have six heating coils or elements 8 which heating coils or elements use 500 watts at 110, 220 or other volts. The switch 9 is so formed that it will have a position off and three positions on, the 45 first permitting use of 1000 watts for all the heating elements, the second, 2000 watts, and the third 3000 watts. While this particular structure is desirable, other arrangements of the heating elements may be used without departing from the spirit of the invention.

The steel plate 5 is comparatively thin and may be held in place in any suitable way, as for instance, by being bolted to the edge of the base plate or by the asbestos cloth 10 being stretched 50 over the plate and secured to the base 3 by suit-

able screws 11. On this asbestos cloth is positioned the matrix 12 which is to be dried, the same being placed in a position face downward. The chamber being previously heated, the matrix may be placed on the asbestos covering or sheeting 65 10 and allowed to dry but the drying would never be successful in that the matrix would wrinkle, buckle or shrink unevenly and not be flat when dried. By the present invention, means have been provided for applying a pressure evenly 70 throughout to the outer surface of the matrix during the drying operation which materially increases the drying action. This holds the matrix firmly against warping, buckling, wrinkling or distorted shrinkage. The result is that the matrix 75 is thoroughly dried and is in a 100 per cent condition after the drying operation. In order to accomplish this, the canvas or other cloth member 13 is provided which is adapted to press against the matrix when the scorching is in use. 80 In order to properly support the canvas 13, a pivotally mounted frame 14 is provided, the same being pivotally mounted through the use of a rod 15 and brackets 16 to a reciprocating frame 17. The frame 14 is provided with angle irons 18 and 85 19, said angle irons having preferably threaded apertures 20 for receiving screws 22, said screws passing through a clamping plate 23 and through one edge of the canvas or other flexible covering 13 for securing the two edges of the covering to 90 the respective bars 18 and 19. Rods 15 and 21 form the end members of the frame 14, which frame is substantially rigid but swings in the brackets 16. A pair of arc-shaped bars or hoops 24 and 25 have their ends riveted to or otherwise 95 connected to the bars 18 and 19 and have their upper parts connected together by a small strip 26. This forms a support for the canvas covering 13, said covering being connected to this support by tape, chains or other flexible members 27. 100 In this way the canvas covering is supported and may be moved upwardly and downwardly without interfering with the action of the canvas on the matrix. The frame 17 is formed from a pair of angle irons 28 and 29 and connecting rods 105 30 and 31, each of said rods having a tube 32 rotatably mounted thereon. Pull rods 33, 34, 35 and 36 depend from the respective bars 28 and 29 and in turn support the bars 37 and 38 which bars are connected by strips 39 and 40, thus 110 making a lower frame to which the respective springs 41 are connected, there being shown four springs though a greater or less number may be used without departing from the spirit of the invention. Each spring is connected with a 115 tension device 42 as shown in Figure 3, each tension device extending loosely through a bracket 44 so that a nut 45 may function to provide any desired tension on the respective springs. Pull rods 33 to 36 inclusive extend loosely through 120

suitable brackets 46 carried by the respective bracing bars 47 and 48. These bracing bars are riveted or otherwise rigidly secured to the respective legs 1 and act in a double capacity as means 5 for bracing the legs and means forming part of the brackets 46. Also the plates 47 and 48 carry their respective shafts 49 and 50 which shafts are rigidly secured to the respective links or cranks 51 and 52, which links or cranks are pivotally 10 connected at 53 and 55 to depending ears on the bar 56. From Figure 3, it will be observed that there are two sets of bars 56 and also two sets of links 51 and 52, whereby the respective bars 56 may be raised and lowered as the links 51 and 52 15 are swung through the action of handle 57 which is rigidly secured to shaft 49. As handle 57 is swung downwardly an appreciable distance, the respective bars 56 will be lowered by the forward and downward swinging movement of the links 20 51 and 52. The bars 56 normally rest against the rollers 32 on rods 30 and 31 and consequently support frame 17 together with the frame 14 which is pivotally mounted thereon. When the bars 56 have been moved downwardly as just 25 described, both frames 14 and 17 will be lowered and consequently the canvas covering 13 will be lowered until it is pressing tightly against the matrix 12. By moving the bars 56 downwardly, the various springs 41 may function to slide the rods 33 to 36 inclusive downwardly and said rods 30 will pull the frames 14 and 17 downwardly. In this way, there is a resilient pressure maintained 35 on the matrix during the drying operation.

As above described, and as shown in Figure 2, 35 frame 14 is pivotally mounted but during the drying operation is locked in its lowered position by the respective catches 58, said catches being pivotally mounted on suitable brackets 59 depending from the respective bars 28 and 29. A 40 rod 60 connects the lower end of these catches while the upper ends engage the respective pins 61. After the drying operation has been completed, which takes approximately one minute when 3000 watts are being used, as above set 45 forth, rod 60 is pushed inwardly and immediately both catches 58 are disengaged from their respective pins 61. As soon as catches 58 have been released the spring 62 surrounding rod 15 and connected to this rod and to member 16 will 50 quickly swing the frame 14 upwardly to the position shown in Figure 2 whereupon the dried matrix may be removed and another matrix substituted. When a new matrix has been placed in position as shown in dotted lines in Figure 3, 55 the frame 14 is swung downwardly and catches 58 move to the position shown in Figure 1. After this has been done, lever 57 is moved downwardly until the bars 56 will not support the frame 17, thus permitting the springs 51 to pull the canvas 60 13 tightly against the matrix. The matrix is left in the necessary time for it to be thoroughly dried and immediately the lever 56 is swung upwardly to the position shown in Figure 1 and then catches 58 released whereupon the frame 14 with 65 canvas 13 is swung upwardly and the matrix may be removed. This operation is continued as often as a matrix is to be dried.

It will be noted that the base plate 3 is provided with the four downwardly extending lugs 70 63 which rest on the rollers 32 so that the frame 17 can be moved upwardly only to a certain point. It is desirable that the canvas 13 be moved upwardly to the position shown in Figures 1 and 3 and left in that position except during the time

of operation of the device, namely, the drying of the matrix, as the heat would injure the canvas if it is allowed to rest on the asbestos covering 10 for any appreciable time. By reason of the use of the canvas 13 and a tension device therefor, the matrix will be perfectly flat and free from uneven shrinkage, buckles or wrinkles regardless of the moisture content thereof. 80

I claim:

1. A scorcher for drying matrices used in connection with printing, comprising a heater structure having a rounded outer surface, an asbestos covering for said surface, said covering being adapted to receive a matrix face down, a cloth sheet normally suspended above said covering, a vertically movable frame and spring means for moving said frame and cloth sheet to a point whereby the sheet will press the matrix against said asbestos covering. 85

2. A scorcher for drying matrices including a heater on which the matrix is adapted to be placed, a sheet of cloth, a swinging frame arranged adjacent the heater, means carried by the frame for normally supporting the sheet of cloth above the heater, means for connecting two 90 of the edges of the sheet to said frame spring means acting on the frame to swing the same downwardly and thereby pull the cloth sheet downwardly until it presses against a matrix on said heater, and manually actuated means for moving said frame upwardly against the action of said springs whereby said cloth will be raised from 95 said matrix. 100

3. A scorcher for drying matrices including a heater adapted to receive a matrix, a cloth for 110 pressing said matrix against the heater and holding the matrix against breaking and buckling during the drying operation, a swinging frame provided with means for supporting said cloth, a reciprocating frame connected to the swinging 115 frame, catch means for locking the swinging frame against the reciprocating frame, a plurality of pull rods connected with the reciprocating frame, means at the lower end of the pull rods tending to pull the pull rods downwardly 120 for moving said frame downwardly until said cloth has pressed against said matrix, and manually actuated means for moving said frame upwardly to cause the cloth to move out of contact 125 with the matrix. 125

4. A scorcher for drying matrices including an arc-shaped heater adapted to receive the matrix, a cloth for pressing the matrix against said heater for holding the matrix against wrinkling and buckling during the drying operation, a reciprocating frame arranged below said heater, a swinging frame pivotally mounted on said reciprocating frame provided with means for supporting said cloth, said frame being adapted to be swung in a vertical plane out of the way to 130 expose the heater when applying and removing a matrix, catch mechanism carried by said reciprocating frame positioned to lock the pivotally mounted frame against said reciprocating frame and in a position to cause said cloth to be 135 substantially parallel with the matrix on the heater, means giving said reciprocating frame continuous tendency to move downwardly, said means acting to move the respective frames and cloth downwardly until the cloth presses tightly 140 against the matrix on the heater and means for raising said frame against the action of the means which tends to lower the same. 145
